WIRE CONNECTOR

Martin D. Bergan, Westfield, N. J., assignor to
 The Thomas & Betts Co., Elizabeth, N. J., a
 corporation of New Jersey

Application June 19, 1940, Serial No. 341,278

1 Claim. (Cl. 173—269)

This invention relates in general to improvements in electrical connecting devices, and more particularly to a new and useful wire connector.

An object of the invention is to produce a wire connector which can be used for quickly and conveniently connecting electrical terminal wires with the pot head of high-tension transformers, or with bus bars, or any other service member or part with which an electrical conductor is to be connected without making a soldered joint.

A further object is to produce a wire connector of minimum number of parts, simple in construction, convenient to install, which is positive and efficient in its electrical contacting connection, and not susceptible of becoming loose once it is installed.

With the foregoing and other objects in view, the invention has relation to the construction and combination of parts as well as the principle herein disclosed and shown by the accompanying drawing illustrating a preferred form or example of the invention, wherein:

Figures 1 thru 5 show several views of the three parts entering into the assembly and combination of this new wire connecting device.

Figures 1 and 2 show, respectively, a side and bottom (inner) end view of an expandable anchorage sleeve forming the larger member of the device.

Figures 3 and 4 show, respectively, a side and bottom (inner) end view of a compression sleeve which slidably fits into the expandable anchorage sleeve.

Figure 5 shows a side view of a jam nut which screws into the outer end of the expandable anchorage sleeve of Figure 1 and forces home the compression sleeve of Figure 3 to electrically join a conductor with a bus bar or other electrical conducting member.

Figure 6 shows a disassembled view of the three parts comprising the device, together with a fragment of stranded electrical cable or terminal wire at the upper part of the illustration, and a fragment of a pot head or bus bar or other service member at the lower end of the view with which the three-part device is adapted to electrically connect the conductor.

Figure 7 shows the assembled connector inserted into a bus bar or service member, together with the stranded conductor in place, and the jam nut ready to be screwed home to make a permanent electrical connection and mechanical anchorage.

Figure 8 shows the ultimate position of the wire connector parts after the jam nut has been screwed home to complete the electrical connection and establish a permanent anchorage of the device in a bus bar or the like.

In the drawing, an electrical conducting wire

W is indicated as adapted to be connected with an electrical service conducting member M. The latter diagrammatically represents a bus bar or other service member or part, say the pot head 5 of a high-tension transformer, with which said wire is electrically and mechanically connected. The electrical service member M is provided with a hole H to receive the device.

This new wire connector comprises three simple parts, to-wit, an expandable anchorage sleeve 10, a compression sleeve 11, and a jam nut 12, the parts being indicated generally by these reference characters. These three parts are shown centrally in Figure 6 in axial alignment and in sequence of assembly. The construction of these parts and their function and use in combination will now be explained.

The expandable anchorage sleeve 10 is of uniform external diameter throughout its effective anchorage length and has a threaded bore 14 of uniform diameter starting at its outer end and extending part way toward its inner end. A tool-receiving head 15 is made on the outer end of the expandable sleeve 10 and usually is in the form of a hexagonal nut. Thus a wrench or other tool can readily grip the knurled or hexagonal nut head 15 for holding the sleeve 10 when installing this wire connector in service position in the member M. A conical bore 16 leads from the inner end of the threads 14 out through the other or inner end of the sleeve 10. This conical bore 16 is smooth and gradually decreases in diameter from the threads to the inner or far end of the sleeve. This sleeve 10 is provided with one or more longitudinal splits 17, say four as shown, extending from the inner end back to the tool-receiving head 15 or adjacent the latter. These splits render the major length of the sleeve radially elastic so that it can be expanded for anchorage within the service member M to electrically connect the wire W thereto.

Coming to the compression sleeve 11, it is somewhat shorter in length than the expandable anchorage sleeve 10. The compression sleeve 11 may be made appropriately in length comparable with the length of the tapered or conical bore 16 in the anchorage sleeve 10. The compression sleeve 11 is split throughout its length as indicated at 19, which renders it radially elastic from end to end, and causes it not only to grip the wire W but also expand the anchorage sleeve 10. The normal expanded size of this radially elastic sleeve 11 when released enables it to easily slip into the threaded end 14 of the larger radially elastic sleeve 10. The compression sleeve 11 also has an internal bore 20 of uniform diameter throughout its length for making a sliding fit with the wire W, and this bore preferably is serrated to bite into the wire. The outer or top portion of the sleeve 11 is of uniform external

diameter as indicated at 21, but decreases in diameter to its inner end as indicated at 22. Thus the compression sleeve 11 has a two-stage external diameter, that is, it is cylindrical at 21 to fit the threaded bore 14 and is conically shaped at 22 to fit the conical bore 16. The external taper 22 of this compression sleeve 11 conforms to the angle of the internal taper 16 of the anchorage sleeve 10.

The nut 12 is also of sleeve form and has a tool-receiving head, say a hexagonal nut 24, with a threaded cuff 25 and an internal bore 26 of uniform diameter to receive the wire W with a sliding fit thereinto. Thus the bore 26 of the nut 12 and the bore 20 of the compression sleeve 11 are the same size for a close sliding fit with the bare end of the wire W after the insulation is cleaned therefrom.

In producing this wire connector, the three parts thereof are formed as above described, the compression sleeve 11 is set into the expandable anchorage sleeve 10, and the nut 12 partly screwed into the bore 14. This holds the parts in assembled relation for shipment and handling purposes. The two operating nuts 15 and 24 are adjacent each other and convenient for holding and turning by a wrench in assembling and separating the parts. The tool-receiving head or hex nut 15 forms a shoulder at the upper ends of the splits 17, and this shoulder acts as a stop adapted to rest or seat against the electrical service member M.

When ready for use, as indicated in Figures 7 and 8, the device is disassembled as shown centrally in Figure 6, or the nut 12 is loosened sufficiently to let the sleeve 11 drop back loose towards the nut and away from the conical bore 16. In this way, the bare end of the electrical conductor wire W can be inserted through both the nut and small sleeve 11 and down into the large sleeve 10. Thus, the assembly of the device and wire W are made ready for insertion into the hole H of the service member M comprising a bus bar, a pot head, or other electrical transmission part.

The anchorage sleeve 10 now is set into the hole H of the electrical terminal member M (Figure 7) with the shoulder of the tool-receiving head 15 seated against said member, the feel of which to the mechanic indicates that the sleeve is fully bottomed in the hole, and the nut 12 is then screwed home (Figure 8). The screwing of the nut 12 into the bore 14 forces the compression sleeve 11 to slide inwardly of the expandable sleeve 10 and as the conical end 22 of the sleeve slides into the conical bore 16 there is produced a substantial pressure expansion of the anchorage sleeve 10 within the member M as shown in Figure 8 and a contraction of the compression sleeve 11 around the wire W. The nut 12 wedges the two coating sleeves 10 and 11 together under great expansive and compression force.

The result is that a true cylindrical contact is established between the entire engaging surface areas of the hole H in the member M and the external cylindrical surface of the anchorage sleeve 10. This large-area engagement establishes a permanent mechanical and efficient electrical connection between the anchorage 70 sleeve 10 and any service member M, as well as

between the cable or wire W and the compression sleeve 20, thereby producing an electrical connection which will not loosen or heat.

This invention is presented to fill a need for improvements in a wire connector. It is understood that various modifications in structure, as well as changes in mode of operation, assembly, and manner of use, may and often do occur to those skilled in the art, especially after benefiting from the teachings of an invention. Hence, it will be understood that this disclosure is illustrative of preferred means of embodying the invention in useful form by explaining the construction, operation and advantages thereof.

What is claimed is:

An electrical connector comprising, in combination, a single anchorage sleeve of uniform external diameter and of smooth formation externally throughout its length adapted to be introduced into a smooth-bore hole or socket of an electrical-conducting service member, a tool-receiving head integrally formed on the outer end of the single anchorage sleeve constituting a stop adapted to seat against the service member to insure full entry of the anchorage sleeve thereinto, the anchorage sleeve having a bore of threaded uniform internal diameter formed through the tool-receiving head and extending inwardly, the bore gradually decreasing in diameter and formed smooth from the inner end of the threads and extending through the inner end of the anchorage sleeve constituting an internal tapering bore, the anchorage sleeve being split longitudinally from its inner end and extending toward its outer end thus rendering it expandable and adapted for anchorage within the smooth-bore hole of the service member as aforesaid; a compression sleeve also split from end to end thereof thus also rendering it expandable, and being somewhat shorter in length than the anchorage sleeve and slidably carried therein, the compression sleeve having a bore of uniform diameter from end to end and being of a size adapting it to receive an electrical conductor with a close sliding fit thereon, the compression sleeve having a two-stage external smooth surface, that is, being uniform in diameter starting at its outer end and extending part way toward its inner end, but gradually decreasing in diameter to said inner end forming an external taper on the same angle as the internal tapering bore of the anchorage sleeve; and a jam nut having a smooth bore also adapted to receive the electrical conductor aforesaid with a close sliding fit thereon, and including an externally threaded cuff screwed into the threaded bore of the anchorage sleeve to force the compression sleeve to slide under pressure within the tapering smooth bore of and toward the inner end of said anchorage sleeve, thereby contracting the compression sleeve for gripping it around the electrical conductor and simultaneously expanding the anchorage sleeve for securing it within the smooth-bore hole of the service member and also establishing a pressure surface-area electrical engagement between said anchorage sleeve and service member throughout their engaging lengths and circumferences of smooth-surface formation.

MARTIN D. BERGAN.
